J. T. AUSTIN,
RESONATOR FOR REED PIPES.
APPLICATION FILED SEPT. 4, 1920.

1,419,486.

Patented June 13, 1922.

J. T. Austin INVENTOR.

BY

Knott, Patterson ATTORNEY.

UNITED STATES PATENT OFFICE.

JOHN T. AUSTIN, OF HARTFORD, CONNECTICUT, ASSIGNOR TO THE AUSTIN ORGAN COMPANY, OF HARTFORD, CONNECTICUT, A CORPORATION OF CONNECTICUT.

RESONATOR FOR REED PIPES.

1,419,486.

Specification of Letters Patent. Patented June 13, 1922.

Application filed September 4, 1920. Serial No. 408,214.

To all whom it may concern:

Be it known that JOHN T. AUSTIN, a citizen of the United States, residing at Hartford, in the county of Hartford and State of Connecticut, has invented certain new and useful Improvements in Resonators for Reed Pipes, of which the following is a specification.

This invention relates to resonators for 10 reed pipes such for instance as are found in pipe organs whether manually or automatically operable. I have a number of objects in view among them being the provision of an article of the character set forth which 15 is capable of inexpensive and very simple construction.

In the drawings accompanying and forming part of the present specification I have shown in detail two of the several forms of 20 embodiment of the invention which to enable those skilled in the art to practice the same will be set forth fully in the following description. I am not restricted to this particular showing. I may depart therefrom in 25 several respects within the scope of the invention defined by the claims following said description.

Referring to said drawings:

Figure 1 is a side elevation of the body of 30 the resonator in original condition.

Fig. 2 is a side elevation of the complete resonator.

Fig. 3 is a front view of the resonator with a reed pipe associated therewith.

Fig. 4 is a cross section on the line 4-4 of Fig. 3.

Fig. 5 is a view corresponding practically to Fig. 3, showing a slight modification.

Like characters refer to like parts throughout the several views.

The resonator which I have selected for illustration in the drawings and shown in its entirety in Figs. 2, 3 and 4 is denoted in a general way by 2. This resonator desirably includes in its makeup, a body as 3 preferably of wood and shown separated from everything else in Fig. 1. This body 3 I prefer to form initially from a practically rectangular block of wood or equivalent material of which there are probably several. I form in the integral or one-piece wooden block, a kerf or slit (Fig. 1), longitudinally thereof. This kerf or slit extends uninterruptedly nearly to the lower end of the

block or body 3 and may be formed for example by a saw or analogous implement. The body or block 3 in addition to the kerf 4 has a transverse bore or passage 5 which may for illustration be formed by a drill, the ends of this bore or passage opening into the sides of the body or block 3 and the bore extending entirely across the block or body. These ends are desirably covered as I will hereinafter set forth. The body or block 3 has, below the transverse bore 5, the longitudinal bore 6 the upper end of which intersects the transverse bore 5 and the lower end of which opens into the lower edge of the body or block 3. While the bore 6 intersects the lower side of the transverse bore 5, the latter in turn is intersected on its upper side by the kerf or slit 4. The formation of the kerf or slit 4 produces upon the upper portion of the body or block 3, the duplicate or complementary wings 7. After the body 75 has been formed in the manner described, the wings 7 are spread or separated in some convenient fashion and this separation makes a tapering passage or slot 8 the walls of the passage or slot converging downwardly from its upper large end toward its lower or small end which is in direct communication with the transverse bore 5.

The sides of this slot 8 are covered by walls 9 which extend from the extreme lower 85 end of the body or block 3 to the upper end thereof as shown both in Figs. 2 and 3, the walls being held in position by nails 10 which are driven through the walls and into the solid part of the body or block, it being 90 understood of course that the upper portions of these walls 9 taper to conform with the exterior configuration of the sides of the body 3. If desired, glue instead of nails may be used to hold these walls in place.

The reed associated with the support 2 may be the same as that shown in Letters Patent 1,323,426 issued to B. G. Austin on December 2, 1919. The reed is denoted in a general way by 11 and in the bore 6 is fitted 100 the tube 12 of the reed.

The modification, (one of several) shown in Fig. 5 differs very little from that described in detail, the body of the modified resonator 2' being denoted by 3', the longitudinal passage of which intersects the transverse bores 5' and 5'', the bore 5' being intersected in turn by the longitudinal bore

6' which is open to a supply of compressed air. In the modified construction the reed 11' is on the side of the resonator, its tube being fitted in the lower bore 5' and its bent 5 portion being extended into the upper bore 5".

It will be clear that I provide a long, thin bar of wood, split centrally for the greater part of its length in a plane parallel to its 10 broader face, the sides being separated to form a Y. The other sides, or edges, of the bar or body are then enclosed. The reed, as will be clear, is connected with the lower end of the body.

15 In the description and claims of this application I have assumed that the resonator is vertical, and have therefore used the terms "upper" and "lower." However, the invention is not limited to a vertical resonator 20 as it is equally applicable to resonators placed in any other desired position, and the relative terms "upper" and "lower" would be changed accordingly.

What I claim is:

25 1. A device of the class described comprising an integral body of wood having wings spread apart to form a passage opening in the sides of the body, the body having a transverse bore intersected by the passage, 30 and walls on the sides of the body completing the sides of the passage.

2. A device of the class described comprising an integral body of wood having wings spread apart to form a passage opening in 35 the sides of the body, the body having a transverse bore intersected by the passage, walls on the sides of the body completing the sides of the passage, the body having, below the transverse bore, a longitudinal

bore opening into the small end of the body 40 and intersecting said transverse bore.

3. A device of the class described comprising an integral body of wood having wings spread apart to form a tapering passage opening into the sides of the body, the latter having a transverse bore intersected by the passage and opening into the sides of the body, walls on the sides of the body completing the sides of the passage, the body having, below the transverse bore, a longitudinal bore opening into the small end of the body and intersecting said transverse bore.

4. A resonator for reed pipes comprising a long, thin bar of wood, split for the greater 55 part of its length in a plane parallel to its broader face, the sides separated and forming a Y, and walls on the sides of the body completing the sides of the passage formed by the split.

5. A resonator for reed pipes comprising a long, thin bar of wood, split for the greater part of its length in a plane parallel to its broader face, the sides separated and forming a Y, and means closing said sides.

6. A device of the class described comprising an integral body having wings spread apart to form a passage opening in the sides of the body, the body having a transverse bore intersected by the passage, and walls on 70 the sides of the body completing the sides of the passage.

In testimony whereof I affix my signature.

JOHN T. AUSTIN.
